UNITED STATES PATENT OFFICE.

EMIL BRECHT AND RUDOLF FUGMANN, OF GUBEN, GERMANY.

MANUFACTURE OF WOOL FELTS.

No Drawing. Application filed May 25, 1926, Serial No. 111,645, and in Germany June 9, 1925.

The invention relates to a process for making woolen felts by the blowing action of air currents. It has already been proposed to work up fine sheeps' wool into felt where-
 5 in the wool was carded and the fibres obtained from the card subjected to the blowing action of currents of air. The felt obtained from this material, however, is not utilizable for many purposes especially in connection with the manufacture of hats. For example, when introducing the fibres into the blowing machine, whilst it is possible to distribute the fibres up to a certain point and allow them to fly through the air and
 10 deposit themselves or settle down, a perfectly uniform deposit is not secured, but on the contrary the fibres repeatedly collect into ball like masses at certain points and this leads to a lack of uniformity.
 15 Now according to the present invention, the primary raw material used is made of the tops, or of the shorter portions of the tops which fall off in combed yarn spinning mills and which when opportunity offers are sometimes made intentionally. This initial product can be introduced directly into the usual blowing machines in which, by the action of air currents, it can be worked up in the usual manner, in the same way as hair
 20 for example. As the tops in contradistinction to carded wool and also to noils represent a stretched fibre, this form being also retained during their passage through the pickers of the blowing machine during the
 25 blowing process, consequently there is obtained just as perfectly uniform and compact deposit upon the cone or other backing as is obtained in the case of hare or rabbit hair, and in this way a much better felt is obtained than from carded wool. The felt meets all requirements and, in particular those of hat manufacture.
 30 Especially good results are secured if either the torn off portions (i. e., waste portions which fall off in combed yarn spinning mills) or the tops, prior to introduction into the blowing machine are cut to a certain length, for example in such wise that the longest fibres are of the same length as hare or rabbit hair.
 35 In the practical application of the process it has been found that it is possible to mix the tops or the torn off portions with hair in any proportion that may be desired and then to work up this mixture also in the manner known in blowing machines. Also in doing this it is advantageous, as set forth above, to so cut the tops or the torn off portions that the longest fibres will have the length of the hair used, preferably hare or rabbits hair.
 40 By the use of the mixture of fibres the advantage is secured that a more compact and firmer felt is obtained whilst it is possible also, according to the proportion of hair in the mixture, to improve the quality of the felt. The possibility of using these two materials simultaneously for purposes of working them up together was not immediately apparent, as there was the doubt whether, when working them up, a non-uniform distribution of the different initial substances might not occur, which would render the production of a useful felt impossible.
 45 The use of the mixture of tops or torn off portions of the tops with hair affords in comparison with the use of carded wool mixed with hair the same advantages as are set forth above in connection with unmixed tops or slivers. Furthermore if it were desired to mix carded wool with hair it would not be possible to obtain a felt that would be useful for the manufacture of hats in particular.
 50 Now according to the present invention, the primary raw material used is made of the tops, or of the shorter portions of the tops which fall off in combed yarn spinning mills and which when opportunity offers are sometimes made intentionally. This initial product can be introduced directly into the usual blowing machines in which, by the action of air currents, it can be worked up in the usual manner, in the same way as hair for example. As the tops in contradistinction to carded wool and also to noils represent a stretched fibre, this form being also retained during their passage through the pickers of the blowing machine during the
 55 blowing process, consequently there is obtained just as perfectly uniform and compact deposit upon the cone or other backing as is obtained in the case of hare or rabbit hair, and in this way a much better felt is obtained than from carded wool. The felt meets all requirements and, in particular those of hat manufacture.
 60 Especially good results are secured if either the torn off portions (i. e., waste portions which fall off in combed yarn spinning mills) or the tops, prior to introduction into the blowing machine are cut to a certain length, for example in such wise that the longest fibres are of the same length as hare or rabbit hair.
 65 In the practical application of the process it has been found that it is possible to mix the tops or the torn off portions with hair in any proportion that may be desired and then to work up this mixture also in the manner known in blowing machines. Also in doing this it is advantageous, as set forth above, to so cut the tops or the torn off portions that the longest fibres will have the length of the hair used, preferably hare or rabbits hair.
 70 By the use of the mixture of fibres the advantage is secured that a more compact and firmer felt is obtained whilst it is possible also, according to the proportion of hair in the mixture, to improve the quality of the felt. The possibility of using these two materials simultaneously for purposes of working them up together was not immediately apparent, as there was the doubt whether, when working them up, a non-uniform distribution of the different initial substances might not occur, which would render the production of a useful felt impossible.
 75 The use of the mixture of tops or torn off portions of the tops with hair affords in comparison with the use of carded wool mixed with hair the same advantages as are set forth above in connection with unmixed tops or slivers. Furthermore if it were desired to mix carded wool with hair it would not be possible to obtain a felt that would be useful for the manufacture of hats in particular.
 80 Now according to the present invention, the primary raw material used is made of the tops, or of the shorter portions of the tops which fall off in combed yarn spinning mills and which when opportunity offers are sometimes made intentionally. This initial product can be introduced directly into the usual blowing machines in which, by the action of air currents, it can be worked up in the usual manner, in the same way as hair for example. As the tops in contradistinction to carded wool and also to noils represent a stretched fibre, this form being also retained during their passage through the pickers of the blowing machine during the
 85 blowing process, consequently there is obtained just as perfectly uniform and compact deposit upon the cone or other backing as is obtained in the case of hare or rabbit hair, and in this way a much better felt is obtained than from carded wool. The felt meets all requirements and, in particular those of hat manufacture.
 90 Especially good results are secured if either the torn off portions (i. e., waste portions which fall off in combed yarn spinning mills) or the tops, prior to introduction into the blowing machine are cut to a certain length, for example in such wise that the longest fibres are of the same length as hare or rabbit hair.
 95 In the practical application of the process it has been found that it is possible to mix the tops or the torn off portions with hair in any proportion that may be desired and then to work up this mixture also in the manner known in blowing machines. Also in doing this it is advantageous, as set forth above, to so cut the tops or the torn off portions that the longest fibres will have the length of the hair used, preferably hare or rabbits hair.

What we claim is:-

1. In a process for the manufacture of felts, introducing substantially straight fibres of combed wool into a blowing machine, and there subjecting said fibres to the action of a current of air for depositing them uniformly upon a receiver in the form of a felt.
2. A process for the manufacture of wool felts by the blowing action of currents of air, which process consists in that fibres of combed wool are cut to such lengths that

the longest fibres are of the same length as hairs used in felt manufacture, such as hare hair, then introduced into the blowing machine and subjected there to the action of 5 air currents which deposit them upon a receiving member to form a felt.

3. A process for the manufacture of felts by the blowing action of currents of air, which process consists in that tops of combed 10 wool are cut into shorter portions and mixed with hair of substantially the same length as said cut portions in any proportion desired, and the mixture is introduced into a blowing machine and there subjected to the 15 blowing action of currents of air for evenly depositing said mixture upon a felt-forming receiver.

4. A process for the manufacture of felts by the blowing action of currents of air, 20 which process consists in that tops of combed wool are cut to substantially the same length as hair used in felt manufac-

ture, such as rabbit hair, then mixed with such hair in any proportion desired, and the mixture is introduced into a blowing machine and there subjected to the blowing action of currents of air for depositing said mixture upon a receiver to form a felt of the desired shape. 25

5. A blown woolen felt consisting of substantially straight fibres of combed wool. 30

6. A blown woolen felt comprising substantially straight fibres of combed wool, 35 said fibres being of substantially the same length as hare hair.

7. A blown felt comprising the shortened tops of combed wool mixed with any desired proportion of hair, said shortened tops being of substantially the same length as said hair. 40

In testimony whereof we have affixed our signatures.

EMIL BRECHT.
RUDOLF FUGMANN.
